United States Patent

Des. 240,523
Patented July 13, 1976

240,523

MENU COVER

Theodor Box, 1108 Aileen Road, Brielle, N.J. 08730

Filed Nov. 5, 1974, Ser. No. 521,078

Term of patent 14 years

Int. Cl. D19—04

U.S. Cl. D19—26

Fig. 1.

Fig. 2.

Fig. 3.

FIG. 1 is a front elevational view of a menu cover showing my new design;

FIG. 2 is a right side elevational view;

FIG. 3 is a bottom plan view;

FIG. 4 is a rear elevational view;

FIG. 5 is an enlarged scale fragmentary cross-sectional view of the front cover taken along line 5-5 of FIG. 1; and

FIG. 6 is a reduced scale perspective view of the menu cover shown in an opened condition.

I claim:

The ornamental design for a menu cover, substantially as shown and described.
